UNITED STATES PATENT OFFICE.

ELMER E. WICKERSHAM, OF STOCKTON, CALIFORNIA, ASSIGNOR TO THE HOLT MANUFACTURING COMPANY, OF STOCKTON, CALIFORNIA, A CORPORATION OF CALIFORNIA.

MUFFLER FOR EXPLOSIVE-ENGINES.

1,344,367.

Specification of Letters Patent. Patented June 22, 1920.

Application filed July 16, 1918. Serial No. 245,183.

To all whom it may concern:

Be it known that I, ELMER E. WICKERSHAM, a citizen of the United States, residing at Stockton, in the county of San Joaquin and State of California, have invented new and useful Improvement in Mufflers for Explosive-Engines, of which the following is a specification.

This invention relates to an explosive engine, and particularly pertains to a muffler therefor.

In view of the fact that the explosions within the cylinders of an internal combustion engine produce loud and objectionable detonations, it is desirable to muffle the sound, at the same time allowing the exhaust gases to pass from the engine cylinders without obstruction.

It is the principal object of this invention to provide a simple muffling device which may be readily disposed over the exhaust pipe of an internal combustion engine, and through which exhaust gases may flow without obstruction, at the same time muffling the sound of the explosion as the gas violently rushes from the engine into the surrounding atmosphere.

The present invention contemplates the use of a circular passageway having a tangential inlet and an axial outlet and, further, formed with a pocket adapted to interrupt the gas and dissipate its force as well as decrease the vibration of the sound waves therein.

Having reference to the accompanying drawings:

Figure 1 is a view in side elevation, illustrating the completely assembled muffler.

Fig. 2 is a view in end elevation, illustrating the device as shown in Fig. 1.

Figs. 3 and 4 are transverse views disclosing the tangential inlet and the radial outlet openings as well as the intervening passageway.

Referring more particularly to the drawings, 10 indicates the exhaust pipe of an explosive engine. This pipe is commonly cylindrical in section and in the present instance is adapted to be fitted with a muffler 11. As a matter of convenience, both in assembly and manufacture, the muffler is made having complementary parts 12 and 13. These parts are united along their contiguous edges by bolting lugs 14 and, when

combined, will be securely clamped around 55 the outer end of the exhaust pipe.

The muffler halves are united to form a circular passageway 15 in communication with the open end of the exhaust pipe by means of a tangential passageway 16. This 60 last named opening is arcuate and leads from the end of the pipe which is preferably disposed in longitudinal alignment with the central axis of the muffler. The central axis of the muffler also coincides 65 with the transverse axes of outlet openings 17 formed through the opposite side walls of the muffler case. These openings are preferably circular and are concentrically disposed in relation to the main passage- 70 way 15.

Formed alongside of the inlet passageway 16 is a sound deadening chamber 18. This chamber is separated from the tangential passageway by an arcuate wall 19 and 75 is further separated from the main annular passageway 15 by an arcuate baffle wall 20. This wall extends from the terminating end of the wall 19 to a point adjacent to the side wall of the muffler, thus forming an 80 inlet port 21. The wall 20 is substantially concentric with the axes of the openings 17. The port 21, leading into the chamber 18, is tangentially disposed in relation to the path of travel of the fluid passing through 85 the muffler and thus tends to dissipate the force of the gases rushing therethrough to deaden the sound produced by the gas as it is emitted from the openings 17 in the case.

In operation, the exhaust gases from the 90 engine will pass into the tangential passageway 16 with great violence and will thereafter be directed in a circulatory path of travel around the annular confining wall of the passageway 16. This will produce a gy- 95 rating motion of the gas as it circumscribes the axes of the openings 17. A centrifugal action will be thus imparted to the gas to retard it in its flow. This gyrating motion will be decreased, due to the fact that some 100 of the gas will pass into the sound deadening chamber 18 and there be muffled. A back pressure of this gas in this chamber will further retard the movement of the main body of gas and decrease its sound 105 vibrations.

As the gas passes around the baffle mem- 110 ber 20 it will be slightly deflected inwardly

and will finally change its path of travel from a circulatory one to an axial one, thereafter flowing outwardly through the opposite openings 17 in the case. Due to the peculiar formation of the case and the manner in which the gas is afforded a long path of travel the violence of the explosion will be dissipated and the gas will pass out into the atmosphere without producing an objectionable detonation. Incidentally the chamber 18 will gather the particles of carbon and extinguish and entrap the flame which would otherwise pass out through the muffler.

15 It will thus be seen that the structure here disclosed while decidedly simple in its formation will effectually reduce the rate of travel of exhaust gases from explosive engines and affect these gases in a manner to 20 dissipate the detonations incident to the explosions within the engine cylinders and the exhaust therefrom.

Having thus described my invention, what I claim and desire to secure by Letters Patent is—

1. A muffler for explosive engines comprising a hollow casing adapted to be disposed in communication with the end of an exhaust pipe, an annular passageway within 25 the casing formed with a peripheral inlet opening, a sound deadening chamber inclosed within the casing having its opening tangentially disposed to the path of travel of gas, and axial outlet ports formed in the 30 opposite sides of the casing wall.

2. A muffler for explosive engines having a circular passageway formed with an inlet opening at the periphery and oppositely disposed axial outlet ports, and a sound-deadening chamber disposed in tangential relation 40 to the path of travel of gas flowing through the passageway and outwardly through the axial ports.

3. A muffler for explosive engines comprising a casing having a cylindrical chamber, an inlet at the periphery of said casing 45 radially disposed, oppositely disposed outlet

openings at the center axially thereof, and a sound deadening chamber communicating with said cylindrical chamber and disposed in the path of travel of the gases, said sound deadening chamber being arranged at a point greater than 180° from the inlet.

4. A muffler for explosive engines comprising a casing having a cylindrical chamber, an inlet at the periphery of said casing radially disposed, oppositely disposed outlet openings at the center axially thereof, a sound deadening chamber communicating with said cylindrical chamber and disposed in the path of travel of the gases, said sound deadening chamber being arranged at a point greater than 180° from the inlet, and means in the form of a baffle plate at the entrance of said sound deadening chamber for assisting in the separation of the solids from the gas and isolating said solids after the same have been separated.

5. A muffler for explosive engines comprising a casing having a cylindrical chamber, an inlet at the periphery of said casing radially disposed, oppositely disposed outlet openings at the center axially thereof, a sound deadening chamber communicating with said cylindrical chamber and disposed in the path of travel of the gases, said sound deadening chamber being arranged at a point greater than 180° from the inlet, means in the form of a baffle plate at the entrance of said sound deadening chamber for assisting in the separation of the solids from the gas and isolating said solids after the same have been separated, and means accessible from the exterior of the muffler for exposing the contents of said sound deadening chamber to permit cleaning of the latter.

In testimony whereof I have hereunto set my hand in the presence of two subscribing witnesses.

ELMER E. WICKERSHAM.
